METHOD OF AND APPARATUS FOR SHAPING
METAL

Marshall H. Ward, Brooklyn, N. Y.

Application January 23, 1929, Serial No. 334,454

44 Claims. (Cl. 153—73)

This invention relates to improvements in methods of and apparatus for shaping metal, and more specifically involving the use of hollow metallic blanks.

5 Both the method and the machine are fundamentally and basically the same as the method and machine disclosed in Patent No. 349,718, issued September 28, 1886, to Hollerith and Metcalf. However, the present method and machine 10 involve numerous improvements hereinafter set forth and described and claimed, resulting in a method and machine capable of high quantity production.

The machine of the Hollerith and Metcalf patent includes a stationary head, a movable head or plunger, operated by fluid pressure, a plurality of partible mold sections within which a hollow blank is positioned, guides for the mold sections and means for admitting fluid pressure into the 15 interior of the hollow blank, and preventing that fluid pressure from exceeding a predetermined amount by suitable relief means. After the blank is placed in position between the stationary head and the movable head with the partible mold 20 sections positioned thereabout and fluid pressure admitted to the interior of the blank, pressure is applied to the movable head so that it will move toward the stationary head, compressing the tube, longitudinally and causing it to bulge out or expand between the mold sections, the movement 25 of the movable head continuing until the mold sections are in contact with each other when the blank will be completely formed according to the internal contour of the mold sections.

30 Fundamentally, the machine disclosed in this present application consists basically of the same broad elements as the machine disclosed in the Hollerith and Metcalf patent and is operated in substantially the same way. This machine includes a bed or frame on which a stationary head and a movable head operated by fluid pressure are mounted; and a forming element composed of a plurality of separate mold sections. Suitable connections are provided for admitting 35 fluid pressure through the stationary head into the interior of the blank, which is positioned within the mold sections and between the stationary head and the movable head. The movable head is operated by fluid pressure, but in this invention, said fluid pressure is from a separate source. The machine is provided with automatic controlling mechanism for controlling the movement of the movable head in both directions, whereby the operation of the machine is rendered to a large extent automatic, adding mate- 40 rially to the flexibility and the speed of operation thereof. The mold sections, as stated, are arranged in spaced relation between the movable head and the stationary head and are adapted to receive a hollow blank therebetween. The par- 45 ticular structure of these sections, whereby they are hinged together so as to be opened to permit the insertion and removal of the work and the locking means therefor, all cooperate to increase the efficiency of the operation of the machine. 50 These mold sections are so supported and guided as to move freely and at random and independently of each other during the forming operation so that they may accommodate themselves to the 55 movement of the material of the blank in expanding and not interfere with the free movement of this material. In other words, these mold sections float or move freely with respect to the work and each other and thereby permit the use of blanks in which the material is of varying or 60 uneven thicknesses and in which this variation may be substantial.

Furthermore, the supporting and guiding means for these mold sections is provided with mechanism for withdrawing the mold sections 65 after the forming operation is complete. This mechanism is selective in the sense that each element thereof engages and moves certain of said mold sections only and moves said sections until they are positioned in a proper position and spaced 70 relation relative to each other for receiving the work blank and starting the forming operation. This movement of withdrawal and positioning and spacing the mold sections is accomplished 75 completely during the retraction of the movable head to its starting position after a forming operation is completed. This mechanism holds the mold sections in their proper position during the insertion of the blank and until the movable head starts its compression movement against the end 80 of the blank when the mechanism is released so that the mold sections are free to move at random and entirely independently with respect to each other during the forming operation.

The apparatus, therefore, includes what might 85 be termed an expandible and contractible mold formed of a plurality of mold sections which are supported so as to be moved freely and independently of each other by the expansion of the material of the blank. These sections are retracted 90 by means actuated by the movable head and selectively engaging the sections and moving and holding them in proper spaced relation to each other until the start of the compression stroke of 95 the movable head.

Among other important structural details from the standpoint of quantity production is the means provided for quick removal of the finished work from the mold sections. This includes a lever to be pressed down by the operator and movable with the movable head so that in its movement it will engage a dog on an operating rod connected to the operating lever which controls the movement of the movable head. The movable head is withdrawn until this lever engages said dog, thereby moving said operating lever to stop the further retraction of the movable head. At this point the mold sections have been moved apart sufficiently to permit the ready and quick withdrawal of the completely formed work therefrom. This prevents sticking of the work within the mold sections due to the force with which it is gripped thereby. Furthermore, this provides a fixed adjustment whereby the mold sections are always opened the proper distance to insure quick removal of the work without damage and without necessitating close care and attention or accurate manipulation of the lever by the operator. After the completed work is removed, the movable head is caused to resume its retracting movement and when near the end of this movement, means connected with the head causes the actuation of the operating lever to stop the movement of the head in proper position to receive the unshaped blank. In this position the mold sections are all accurately and properly spaced with respect to each other.

There are numerous other improvements in details of construction which will be apparent from a reading of the following specification and claims, and a consideration of the drawings. The new and improved method includes the shaping of a hollow metal blank, filled with fluid under pressure, within an expandible and contractible mold formed of a plurality of mold sections by the application of longitudinal or axial pressure to the blank, the mold sections, under the influence of the expanding metal, moving freely or floating at random with respect to each other and accommodating themselves to the movement of the expanding material and not restricting the same except as it fills the mold.

To the accomplishment of the foregoing, and such other objects as may hereinafter appear, this invention consists in the construction, combination and arrangement of parts and the method hereinafter described and sought to be defined in the appended claims, reference being had to the drawings forming a part hereof, and which show merely for the purpose of illustrative disclosure, one form of mechanism adapted to practice the method and embodying this invention, it being expressly understood that the method may be practiced by other forms of apparatus, and that changes in the apparatus may be made in practice within the scope of the claims without digressing from my inventive idea.

In the drawings,

Fig. 1 represents a side elevation of a machine adapted to practice the method of this invention and constituting one embodiment of the invention; the movable head being shown in its retracted position, the forming element being omitted entirely, and the source of fluid pressure supplied for the interior of the hollow blank through the stationary head being omitted;

Fig. 2 is an end elevation of the apparatus shown in Fig. 1 taken from the left-hand end of the same;

Fig. 3 is an end elevation of the apparatus,

shown in Fig. 1 taken from the right-hand end of the same;

Fig. 4 is a view of the construction of the forming element primarily in front elevation, a number of parts, however, being broken away and being shown in section to facilitate the disclosure, the parts being shown in proper position for receiving the work and starting the shaping operation;

Fig. 5, in general, is a view in longitudinal and vertical cross-section of the structure shown in Fig. 4, parts being shown in elevation, the mold sections and associated parts and the stationary head and movable head and the work being shown in the positions attained at the completion of the shaping operation, which is previous to any retraction or releasing movement of the movable head;

Fig. 6 is a vertical transverse cross-section taken substantially along line 6-6 of Fig. 4, looking in the direction of the arrows;

Fig. 7 is a view in vertical transverse cross-section taken substantially on line 7-7 of Fig. 4, and looking in the direction of the arrows;

Fig. 8 is a view in vertical transverse cross-section taken substantially on line 8-8 of Fig. 4, looking in the direction of the arrows;

Fig. 9 is a side elevation of one of the mold sections, the locking and supporting and guiding means being shown in section, and different positions being indicated in dotted lines;

Fig. 10 is a diagrammatic view, mostly in section, of the guiding and supporting means for the mold sections, showing the mold sections in spaced positions assumed at the conclusion of the retraction movement of the movable head and previous to the initiation of the shaping movement; and

Fig. 11 is a view similar to Fig. 10, showing the same parts in the position assumed at the completion of the shaping operation.

Referring, first, to Figs. 1, 2 and 3 of the drawings, the numeral 20 designates a suitable bed or table upon which the apparatus is mounted. The stationary head, designated generally as 21, is positioned to the left in Fig. 1, and the movable head, designated generally as 22, is positioned to the right thereof. The stationary head 21 includes the main body 23 movably mounted for limited movement upon the short hollow shaft 24 extending from a suitable support or bracket 25. The conduit 26 connects the hollow shaft 24 with the fluid-pressure control valve mechanism 27, which controls the fluid pressure supplied through conduit 28 from an accumulator or other suitable source of supply. The main body of the stationary head is hollow, and has its extreme right-hand end reduced and threaded as at 29 to receive a suitable nipple member 30. (See Fig. 5.) This nipple member has the shoulder flange 31 and the internally screw-threaded portion 32 to fit corresponding parts of the main body 23, and at its other end is provided with a recess 33 in which is mounted a washer or other suitable packing member 34. It is to be noted that this washer or packing member is less in width than the depth of the recess so that an annular flange portion 35 remains to receive the flanged end of the blank, as herein-after described.

This body 23 and its attached nipple member 30 has a limited movement as previously mentioned, and the actuating means therefor will now be described. An operating lever 36 is pivoted to the frame as at 37 and has the bell-

crank member 38, to the end of which is pivotally connected a link 39, which is pivotally connected to another link 40 intermediate its ends. This link 40 is pivoted to the frame at 41 at one end and at its other end is pivoted as at 42 to another link member 43, which is pivotally connected as at 44 to the body 23, forming a toggle construction. A link 45 is pivotally connected at one end to the bell-crank arm 38 and at its other end to the hydraulic valve operating cam 46. This cam is pivotally connected to the frame as at 47 and has the cam groove 48 at one end, to slidably receive the pin 49 connected to one end of the valve stem 50.

With the parts in the position shown in Fig. 1 of the drawings, the body 23 of the head 21 is shown in the position assumed during the shaping operation—that is, the head has been sealed against the blank so as to permit the entrance of fluid under pressure thereinto, the hydraulic valve being open for this purpose. When the operating lever 36 is moved from its full-line position to its dotted-line position, the hydraulic valve will be closed, relieving the interior of the work of the hydraulic pressure and then the body 23 is moved to the left to break the seal which releases whatever fluid remains within the work. On the other hand, when the work is positioned in the apparatus previous to shaping, the lever 36 is moved to the right which first causes the body 23 to move to the right and the head to seal against the end of the work, and further movement of the lever through movement of the cam 46 opens the hydraulic valve to admit fluid pressure within the blank.

Referring now to the movable head construction 22, the numeral 51 designates generally a fluid-pressure operated ram including a cylinder 52 with a piston therein having a piston rod 53 connected to the ram head 54. The movements of this piston rod and ram head are controlled by fluid pressure admitted into either end of the cylinder through conduits 55 and 56, which are connected to a variable pressure, variable delivery, reversible delivery, fluid pump 57. This pump is driven by a suitable motor 58, and said pump is also provided with the pressure-control device 59 which is connected by a series of links 60 with the control or operating lever 61. Movement of this control lever in either direction, as indicated by the angular lines, will place the pump on stroke in either direction. This produces an inward or outward movement of the ram head 54, and the rate of this movement is varied in the extent to which the control lever is moved one way or the other.

The forming element will now be described, and reference will be first had particularly to Figs. 4 to 9, inclusive, it being understood that except for the supports therefor, the showing of this forming element is omitted from Fig. 1 of the drawings.

A pair of suitable supports 62 and 63 are mounted upon the bed or table and secured in proper spaced relation. The support 62 is located adjacent the stationary head and in fact is so formed as to permit the movement of the nipple 30 thereinto, as clearly shown in Fig. 5 of the drawings. The support 63 is positioned adjacent the ram and is constructed so as to permit the passage of the piston rod 53 therethrough. This support 63 is shown in detail in Fig. 6 of the drawings.

A plurality of mold sections, designated generally 64, are positioned between said supports

and are movably supported by means of a plurality of shafts 65, which are slidably mounted and supported by said supports 62 and 63. These supports themselves and the mold sections are preferably formed in two parts hinged together at one side so as to be separable and portable in order to permit the ready insertion of the blank and removal of the completed work. This hinge is provided by means of the shaft 66 which extends from one support 62 to the other support 63, and on which the two parts 64^a and 64^b of the mold sections are hinged. The two parts 62^a and 62^b and 63^a and 63^b of the supports are also hinged on this shaft, and the parts 62^a and 63^a of the supports, and the parts 64^a of the mold sections are all adapted to be moved into open and closed position together.

Referring particularly to Fig. 9, which is an illustration typical of all of the mold sections, with the exception of the first mold section, it is seen that each comprises a plate of general rectangular shape, divided into two parts 64^a and 64^b hinged together upon the shaft 66, as previously described. These parts are preferably provided with an interlocking tongue and groove construction 67, and the upper part 64^a is provided with an outwardly extending lug 68 adapted to be engaged by a suitable lock or latch construction 69, one being provided for each of said mold sections. It is in the form of an arm, as shown, having an opening 70 to receive the lug 68, the upper edge of the opening frictionally bearing against the slightly curved top surface of the lug, as clearly shown in Fig. 9. Each arm 69 is pivoted or hinged with respect to the lower section 64^b and for convenience this pivot is provided by the rod or shaft 71 extending entirely across the face of the forming element from support 62 to support 63, being mounted in said supports. At the end of said rod or shaft 71 and opposite the supports 62 and 63, I provide the heavier supporting arms 72 to which the frame member 73 is attached, extending entirely across the front face of the forming element. To this member 73, I attach a suitable operating handle 74. It is seen, therefore, that when the operating handle is moved to the left, looking at Fig. 6, all of the latches 69 will be released, as indicated in dotted lines in Fig. 9, and, conversely, when the handle 74 is moved to the right in Fig. 6, all of the lugs 68 will be engaged by the latch member 69 and the mold sections locked together.

Each of the mold sections 64 is provided with a central aperture 75, the diameter of which is the approximate outside diameter of the blank. The portion of each mold section adjacent this aperture 75 is formed or shaped to provide part of a mold structure 76, all of said mold sections cooperating to form the complete mold when moved into contact with each other, as illustrated in Fig. 5. In this disclosure, this mold formation is similar—that is, each mold section is similarly shaped, but it is to be understood that this is for illustrative purposes only, and the sections may be shaped differently from each other, the only requirement being that they cooperate to produce a completed mold section when brought into contact with each other so as to give the desired shape to the article when completely formed.

Each mold section is provided with a plurality of apertures 77 to permit the passage of the shafts 65 therethrough. These apertures are of substantially greater diameter than the diameter of

- the shafts. However, in one aperture of each of the parts 64^a and 64^b of each mold section, I place a bushing member 78. This bushing member is long so as to give the mold section an extended bearing on the shaft 65 passing therethrough. This bushing is provided with a plurality of grooves 79 longitudinally extending therethrough and arranged radially around the inner surface, one portion 80 of the bushing being left blank or ungrooved to serve as a shoulder or abutment to be engaged by parts to be described later. These bushings are preferably arranged in different apertures in the adjacent mold sections for a purpose to be described later.
- 18 The first mold section—that is, the one shown to the extreme left in Figs. 4 and 5 of the drawings, designated 64^a—is slightly different from the other mold sections in that the apertures 77 therein are all free and no bushings are used at all. Furthermore, both parts are permanently fastened to the support 62. This support is provided with a plurality of apertures arranged in alignment with the apertures in the mold sections and a plurality of longitudinal grooves 81 are formed radially around said apertures. The other support 63 is suitably bored or apertured as at 82 to slidably receive the shafts 65, each of which is provided with an extending key 84 slidably received in a groove or key-way 83 positioned in said bore or aperture 82, to prevent the shaft from turning relatively to the supports.
- 18 The shafts 65 in the embodiment illustrated in the drawings, are actually what might be termed "composite" shafts, being composed of the external tubular shaft 85 with a plurality of smaller shafts 86 mounted therein. These smaller shafts are resiliently held in spaced relation to each other by means of spring members 87 and the end shafts 86' project beyond the ends of their respective hollow shafts 85 to engage a stationary abutment plate 88, this abutment plate being attached to a stationary part of the mechanism. Each of the hollow shafts 85 has extending outwardly therefrom a plurality of lugs or pins 89 which are arranged thereon at suitable intervals longitudinally and also angularly so as not to be in longitudinal alignment with each other. These hollow shafts 85 are also provided with a plurality of elongated slots 90 also extending longitudinally and arranged in the same angular relation with respect to the lugs or pins 89 previously referred to. The shafts 86 are each provided with an abutment member 91 securely fastened thereto, and part of it extends into and through one of said slots 90. It is therefore understood that one each of said pins or lugs 89 and one each of said abutment members 91 are arranged in longitudinal alignment with respect to each other.
- 60 While I have described the inner shaft 86 as being composed of a plurality of short sections, it is to be understood that this may be made in the form of one shaft, if desired, with the abutment members 91 similarly secured thereto in the same relative arrangement.
- 60 The lugs or pins 89 and the abutment members 91 constitute, in connection with the bushings 78, means for selectively engaging and moving the mold sections to their proper spaced position during the retraction of the ram head from its extended position back to the initial or starting position. In other words, and in greater detail, the pins or lugs 89 engage the blank space 80 in certain of the bushings in certain of the respective mold sections abutting thereagainst, and cause the movement of said mold sections back to the initial or starting position. The abutment members 91 engage said bushings on the side opposite the lugs or pins 89 and serve to clamp the bushings between the lugs or pins 89 and the abutment members 91, and thereby hold the respective mold sections in their proper spaced position during the insertion of the work therein prior to the starting of the forming operation.
- 60 It is to be particularly noted that the upper mold section 64^a with the shafts 65 therefor constitute one assembly, and the lower mold section 64^b with the shafts 65 therefor form another assembly, which is a duplicate as far as the arrangement of the pins and lugs 89 and abutment members 91 is concerned. Furthermore, the pins or lugs 89, as well as the abutment members 91 on each composite shaft 65, are arranged in different positions with respect to the pins or lugs 89 and the abutment members 91 of the other shaft 65 in the same assembly, and these pins or lugs and abutment members are preferably arranged progressively so as to engage the proper bushing progressively and move the proper mold section progressively with respect to the other mold sections.
- 60 In the embodiment illustrated, it is to be noted that each of said composite shafts 65 is provided with three sets of lugs or pins 89 and abutment members 91 so that each shaft 65 is responsible for and causes the movement of three mold sections.
- 60 As previously stated, the selection of the proper mold section and its movement is caused by the engagement of the lug or pin 89 with the shoulder 80 in the bushing. Of course, it is understood that the number of mold sections, the number of shafts, and the arrangement and number of the lugs or pins 89 and abutment members 91 on each shaft 65 may be varied to meet various working conditions and desired results.
- 60 By providing the plurality of grooves 79 in the various bushings it is seen that the pins or lugs 89 and the abutment members 91 have free movement with respect to all of the mold sections, except the particular one which the pin or lug 89 is adapted to engage and move.
- 60 The means for moving the composite shaft 65 upon the retraction of the ram head will now be described. This includes a yoke member 92 which is suitably fastened to the rear part of the ram head. This yoke member is formed of two parts 93 and 94 hinged upon shaft 66. Each of the sections 93 and 94 of the yoke member is provided with a plurality of openings 95 therethrough, arranged in alignment with the openings through the mold sections. These openings are of sufficient size to slidably receive sleeves 96 which are secured by any suitable means to the hollow shafts 85. One part of these sleeves 96 is screw-threaded so as to adjustably receive the adjusting and lock nuts 97 and 98. The adjusting nut 97 affords a shoulder on each sleeve 96 adapted to be engaged by the face of the yoke 92 during the retracting movement of the ram head. This adjusting nut construction provides a simple and effective method of properly positioning the composite shafts 65 at all times with respect to each other so as to insure the proper operation in retracting and spacing the mold sections. While the yoke 92 engages the adjusting nut 97 during the retracting movement, the parts, however, are so arranged that during the forward movement of the ram head, the adjusting nut is 150

spaced from the yoke because the yoke will move away from the adjusting nuts, as clearly shown in Fig. 5 of the drawings. This is important in that it insures free and unrestricted movement of the shafts during the forward movement of the ram head and during the entire shaping operation. The yoke serves as a support for the ram head and is slidably supported upon the two longitudinal supporting shafts or rods 92', which are in turn supported in fixed relation in the supports 62 and 63.

It is now in order to describe the general operation of the forming element just described. Assuming that the parts are in the position in Fig. 4 of the drawings, the latch 69 is released and the mold sections opened and the blank is placed in position with one end against the face of the ram head, the blank being supported by the lower mold sections. The top mold sections are then brought down into engagement with the blank and the latch secured. The stationary head is moved to cause the packing or washer 34 to engage the end of the blank, forming a fluid-tight seal, and fluid pressure is admitted to the interior of the blank. When the desired fluid pressure is reached within the blank, then pressure is admitted to the piston of the ram, causing the ram head to move axially or longitudinally with respect to the blank and to apply pressure to the blank in that direction. The moment the ram head moves to the left at the beginning of the forming operation, all of the shafts 65 are released and become free and unrestrained so that they and the mold sections as well may move at random at all times during the forming operation and until the mold sections are brought into contact, as shown in Fig. 5 of the drawings. Therefore, the mold sections are moved only by the movement of the blank as it changes form or shape due to the pressure and longitudinal movement of the ram head thereagainst and the constantly maintained internal pressure. There is no system of any kind whatsoever about the movement of the mold sections and they move only in exact accordance with the forming requirements of the blank in each particular operation. Of course, the movement of these mold sections varies in different operations due to variation in the wall thickness of the particular blank being shaped and in successive operations due to variation in the wall thickness of the successive blanks being shaped. In other words, the mold sections are entirely free to accommodate themselves to the individual actions of any particular blank or any part thereof during the forming operation. Obviously, there is no studied or systematic effect, whereby each part of the blank has to be operated upon in exactly the same way. The mold sections automatically accommodate themselves to the characteristics of each particular blank.

As this forming movement continues, the shafts 65 are moved along due to the engagement of the abutments formed by the blank spaces 80 of the bushings with the pins or lugs 89, the abutment members 91 lagging behind and being free of contact with any bushing. This statement applies to the particular bushings and mold sections which are controlled by any one shaft because there is no connection at all between the other bushings and mold sections and any other shafts, as the shafts have entire freedom of operation with respect to such mold sections because the pins or lugs 89 and the abutment members 91 may freely pass through the grooves 81 in

both directions. This is true in its entirety of the first mold section 64' because there are no bushings in that mold section at all. The shafts also have free movement through the end support 62 because of the complete series of grooves formed in the openings therethrough, and, of course, the shafts have free movement in the other support 63 because the lugs or pins 89 and the abutment members 91 do not reach that support at any stage of the operation.

The detailed relative arrangement and operation of these parts is shown in Figs. 4 and 5, and particularly in all the diagrammatic views, Figs. 10 and 11. These views are taken as if the mold sections were opened up and are for the purpose of showing the relative position of the mold sections and the composite shafts 65, first, at the initial or starting position, and, second, at the completion of the forming operation. The mold sections are designated by the numbers 1 to 13, inclusive, beginning at the left-hand side of the forming element. The shafts are designated, for convenience, *a*, *b*, *c* and *d* in one assembly, and *a'*, *b'*, *c'* and *d'* in the other assembly.

For illustration, reference will be made to one pair of shafts only and the mold sections controlled thereby, as a description of one will suffice for all. Shaft *a* has its pins or lugs 89 and abutment members 91 arranged so as to control the retraction and proper positioning of the mold sections 2, 6 and 10, respectively, and shaft *a'*, which is oppositely positioned to shaft *a* in the other assembly, likewise controls the same mold sections of its assembly, having no control or operative relation with any of the other mold sections at all. It is to be recalled that the pins or lugs 89 and the abutment members 91 are arranged in different positions angularly with respect to each other. This is not shown in Figs. 10 and 11, because these are diagrammatic views only, but Figs. 4 and 5 show that arrangement, which, of course, is for the purpose of restricting the operation of any one of said pins or lugs 89 to one mold section only, the grooves in the other bushings being positioned so as to permit the free passage of that pin and its complementary element 91 freely therethrough.

It is to be noted that the forming element is actually an expansible and contractible mold formed of a plurality of mold sections. In the embodiment of this invention illustrated, one end of this mold is formed as part of the ram head. See particularly Figs. 4 and 5. The ram head is suitably recessed at 99 to receive the end of the blank and is also formed or recessed at 100 to provide a mold section adapted to cooperate with the mold section formed on the adjacent face of the adjacent mold section 64, being numbered 13 in the diagram.

In order to facilitate the operation of this apparatus and to render the same automatic to a large extent, and also to avoid inefficient operation because of inefficient operators, I provide means for automatically controlling the operation of the ram. For this purpose, I provide a rod 101, which is movably mounted in a suitable position on the frame. This rod 101 has the link connection 102 with the lever or operating arm 61. On the forward or left-hand portion of the rod (see Fig. 1) I provide a knock-off dog 103 and at an intermediate position, a second knock-off dog 104. These dogs 103 and 104 are adapted to be engaged by suitable elements connected to move with the yoke 92 so as to move the rod 101 and thereby move the oper-

ating lever 61 back to neutral position and thereby stop the movement of the ram head at certain desired times.

I provide an engaging lever 105, which is pivotally mounted with respect to the yoke 92 and moves therewith. This lever is provided with the operating handle 106 and a yoke-engaging part 107, adapted to fit over and slide upon the rod 101. (See Fig. 6.) This lever 105 is normally held in raised position, but when the forming operation is complete, it is depressed and moved into engagement with said rod 101, so that when the operating lever 61 is moved to the left so as to start the withdrawal or retraction of the ram head, the yoke, moving with the ram head and carrying the lever 105, will eventually cause the engagement of that lever with the knock-off dog 103, thereby moving the rod 101 to the right and the operating lever 61 to the right into neutral position, so as to stop the withdrawal of the ram head. The position of the knock-off dog 103 is fixed so as to stop this movement when the parts have moved apart sufficiently to permit the ready withdrawal of the completed work from the mold sections. The mechanical pressure, of course, is released and the residual fluid pressure is reduced to a very low value.

The yoke 92 is also provided with an extension 108 having a fork 109 at its end adapted to fit over and move upon the rod 101. (See Fig. 7.) This fork is adapted to engage the knock-off member 104 near the end of the retracting movement of the ram head and is so positioned as to cause sufficient movement of the rod 101 and the operating lever 61 connected thereto as to cause the latter to assume a neutral position when the ram head has reached the end of its retracting movement. This insures that this movement will always be the same length and that the mold sections will always be retracted the proper distance to insure accurate spacing with respect to each other. This construction also permits extremely rapid retraction because the automatic cut-off prevents the necessity of the operator's doing anything to insure a stopping movement of the ram head at its proper position. This is done automatically.

It is, of course, understood that various parts of this apparatus may be removed and other parts used in place thereof so that each apparatus may be used on work of different sizes and of different kinds. Both the nipple member 30 and the ram head 54 may be changed and the mold sections 64 may be changed in number and arrangement. These mold sections may also have their forming portions formed of different and various shapes from those shown in the drawings.

The apparatus described and illustrated and which represents only one embodiment of this invention is designed primarily for corrugating thin-walled hollow metallic tubes to make hollow resilient metallic bellows. It is to be noted that the mold sections are comparatively thin and comparatively light, and therefore may be readily moved under the influence of the expanding metal during the shaping operation. However, the machine is adapted for the formation of various other articles merely by changing the parts above referred to.

What I claim is:

1. In combination, in an apparatus for shaping metal from a hollow blank, an expansible and contractible mold formed of a plurality of mold sections supported so that they may move free-

ly and at random under the influence of the expanding metal of the blank when the blank is subjected to internal fluid pressure and external longitudinal or axial pressure, and means for selectively retracting said mold sections and moving them into their initial starting position properly spaced with respect to each other.

2. In combination, in an apparatus for shaping metal from a hollow blank, an expansible and contractible mold formed of a plurality of mold sections supported so that they may move freely and at random under the influence of the expanding metal of the blank when the blank is subjected to internal fluid pressure and external longitudinal or axial pressure, and means for selectively retracting said mold sections and moving them into their initial starting position properly spaced with respect to each other, said means being inoperative with respect to said mold sections during the shaping operation.

3. In combination, in an apparatus for shaping metal from a hollow blank, an expansible and contractible mold formed of a plurality of mold sections supported so that they may move freely and at random under the influence of the expanding metal of the blank when the blank is subjected to internal fluid pressure and external longitudinal or axial pressure, each mold section being composed of two parts hinged with respect to each other so that each mold section may be opened, and means for opening said mold sections.

4. In combination, in an apparatus for shaping metal from a hollow blank, an expansible and contractible mold formed of a plurality of mold sections supported so that they may move freely and at random under the influence of the expanding metal of the blank when the blank is subjected to internal fluid pressure and external longitudinal or axial pressure, each mold section being composed of two parts hinged with respect to each other so that each mold section may be opened, means for opening said mold sections, and means for locking said parts of the mold sections together, said locking means being operable as a unit.

5. A machine for shaping metal from a hollow blank, including in combination, a stationary head, a movable head or ram with means for applying pressure thereto, a forming element including a plurality of mold sections positioned between said stationary head and said movable head, said mold sections being so formed that when closed they provide a complete mold for the blank, means for movably supporting said mold sections so that they may move freely and independently with respect to each other and longitudinally of the blank and under the influence of the expanding metal of the blank when the blank is subjected to internal pressure and external longitudinal or axial pressure and means cooperating with said head or ram for initially correctly spacing said mold sections.

6. A machine for shaping metal from a hollow blank, including in combination, a stationary head, a movable head or ram with means for applying pressure thereto, a forming element including a plurality of mold sections positioned between said stationary head and said movable head, said mold sections being so formed that when closed they provide a complete mold for the blank, means for movably supporting said mold sections so that they may move freely and independently with respect to each other and longitudinally of the blank and under the influence of the expanding metal of the blank when the blank is subjected to internal pressure and external longitudinal or axial pressure and means cooperating with said head or ram for initially correctly spacing said mold sections.

influence of the expanding metal of the blank, said supporting means being provided with elements adapted to selectively engage various mold sections during the retracting movement of the movable head, and an operative connection between said movable head and said supporting means, whereby when the movable head is retracted, the mold sections will be selectively moved to their initial starting position and properly spaced with respect to each other.

10 7. A machine for shaping metal from a hollow blank, including in combination, a stationary head, a movable head or ram with means for moving said movable head in both directions, a forming element including a plurality of mold sections positioned between said stationary head and said movable head, said mold sections being so formed that when closed they provide a complete mold for the blank, means for movably supporting said mold sections so that they may move freely and independently with respect to each other and longitudinally of the blank and under the influence of the expanding metal of the blank, said supporting means being provided with elements adapted to selectively engage various mold sections during the retracting movement of the movable head, and an operative connection between said movable head and said supporting means, whereby when the movable head is retracted, the mold sections will be selectively moved to their initial starting position and properly spaced with respect to each other, the engagement of said elements with said mold sections being non-effective during the entire forward movement of the movable head.

25 8. A machine of the character described, including in combination, a stationary head, a movable head, means for moving said movable head under pressure, a forming element for a hollow metallic blank, including spaced supports, a plurality of shafts slidably mounted in said supports, a plurality of mold sections mounted upon said shafts between said stationary head and said movable head, said mold sections being movable freely and independently with respect to each other during the forward movement of the movable head so that they may accommodate themselves longitudinally with respect to the blank under the influence of the expanding metal of the blank.

30 9. A machine of the character described, including in combination, a stationary head, a movable head, means for moving said movable head under pressure, a forming element for a hollow metallic blank, including spaced supports, a plurality of shafts slidably mounted in said supports, a plurality of mold sections mounted upon said shafts between said stationary head and said movable head, said mold sections being movable freely and independently with respect to each other during the forward movement of the movable head so that they may accommodate themselves longitudinally with respect to the blank under the influence of the expanding metal of the blank, each of said shafts being provided with an engaging element adapted to engage one of said mold sections and move said mold section back to its initial starting position, and an operative connection between said movable head and said

35 shafts to cause the retracting movement of the shafts and the mold sections controlled thereby.

10 10. A machine of the character described, including in combination, a stationary head, a movable head, means for moving said movable head under pressure, a forming element for a hollow

metallic blank, including spaced supports, a plurality of shafts slidably mounted in said supports, a plurality of mold sections mounted upon said shafts between said stationary head and said movable head, said mold sections being movable freely and independently with respect to each other during the forward movement of the movable head so that they may accommodate themselves longitudinally with respect to the blank under the influence of the expanding metal of the blank, each of said shafts being provided with an engaging element adapted to engage one of said mold sections and move said mold section back to its initial starting position, an operative connection between said movable head and said shafts to cause the retracting movement of the shafts and the mold sections controlled thereby, each shaft also having another engaging element resiliently mounted with respect to the shaft and adapted to engage the opposite side of the same mold section so as to assist in holding the mold section in its proper starting position.

15 11. A machine of the character described, including in combination, a stationary head, a movable head, means for moving said movable head under pressure, a forming element for a hollow metallic blank, including spaced supports, a plurality of shafts slidably mounted in said supports, a plurality of mold sections mounted upon said shafts between said stationary head and said movable head, said mold sections being movable freely and independently with respect to each other during the forward movement of the movable head so that they may accommodate themselves longitudinally with respect to the blank under the influence of the expanding metal of the blank, each of said shafts being provided with an engaging element adapted to engage one of said mold sections and move said mold section back to its initial starting position, an operative connection between said movable head and said shafts to cause the retracting movement of the shafts and the mold sections controlled thereby, each shaft also having another engaging element resiliently mounted with respect to the shaft and adapted to engage the opposite side of the same mold section so as to assist in holding the mold section in its proper starting position.

20 12. A machine of the character described, including in combination a stationary head and a movable head and means for moving said movable head in both directions, a pair of supports, a plurality of shafts slidably supported in said supports, a plurality of separate mold sections supported upon said shafts and positioned between said stationary head and said movable head, an operative connection between said movable head and said shafts effective during the retracting movement of the movable head only to cause a corresponding movement of said shafts, each shaft being provided with means adapted to selectively engage one of said mold sections during the retracting movement of the shaft and to move that mold section in its proper starting position.

25 13. A machine of the character described, including in combination a stationary head and a movable head and means for moving said movable head in both directions, a pair of supports, a plurality of shafts slidably supported in said supports, a plurality of separate mold sections supported upon said shafts and positioned between said stationary head and said movable head,

- an operative connection between said movable head and said shafts effective during the retracting movement of the movable head only to cause a corresponding movement of said shafts, each shaft being provided with a plurality of engaging means adapted to selectively engage a plurality of said mold sections and to move them back to their proper starting position during the retracting movement of said shafts.
- 10 14. A machine of the character described, including in combination a stationary head and a movable head and means for moving said movable head in both directions, a pair of supports, a plurality of shafts slidably supported in said supports, a plurality of separate mold sections supported upon said shafts and positioned between said stationary head and said movable head, an operative connection between said movable head and said shafts effective during the retractive movement of the movable head only to cause a corresponding movement of said shafts, each shaft being provided with means adapted to selectively engage one of said mold sections during the retracting movement of the shaft and to move that mold section in its proper starting position, and means resiliently mounted with respect to each shaft for engaging the opposite side of said mold section to hold the mold section in its proper starting position.
- 15 15. In combination, in a machine of the character described, an expandible and contractible mold including a plurality of mold sections, each mold section being provided with a plurality of apertures, a plurality of shafts passing through said apertures in said mold sections, said shafts being less in diameter than said apertures, bushings positioned in certain apertures in certain mold sections, said bushings slidably fitting said shafts, each bushing being provided with a plurality of grooves radially arranged and also having an abutment, each shaft having an engaging element positioned in alignment with said abutment and operative on the withdrawal movement of said shafts to engage said abutment so as to move that mold section back to its proper starting position, and means for moving said shafts sufficiently so as to properly position said mold sections.
- 20 16. In combination, in a machine of the character described, an expandible and contractible mold including a plurality of mold sections, each mold section being provided with a plurality of apertures, a plurality of shafts passing through said apertures in said mold sections, said shafts being less in diameter than said apertures, bushings positioned in certain apertures in certain mold sections, said bushings slidably fitting said shafts, each bushing being provided with a plurality of grooves radially arranged, and also having an abutment, each shaft having an engaging element positioned in alignment with said abutment and operative on the withdrawal movement of said shafts to engage said abutment so as to move that mold section back to its proper starting position, and means for moving said shafts sufficiently so as to properly position said mold sections.
- 25 17. In combination, in a machine of the character described, an expandible and contractible mold, including a plurality of mold sections, each mold section being provided with a plurality of apertures, a plurality of shafts passing through said apertures in said mold sections, said shafts being less in diameter than said apertures, bushings positioned in certain apertures in certain
- mold sections, said bushings slidably fitting said shafts, each bushing being provided with a plurality of grooves radially arranged and also having an abutment, each shaft having a plurality of engaging elements positioned in alignment with said abutments by a plurality of said bushings, said abutments and said engaging elements being arranged at different radial positions with respect to each shaft, and operative on the withdrawal movement of said shafts to engage said abutment so as to move that mold section back to its proper starting position, and means for moving said shafts sufficiently so as to properly position said mold sections.
- 30 18. In combination, in a machine for shaping metal, a stationary head and a movable head adapted to have a hollow blank clamped therebetween, means for admitting and maintaining fluid pressure within said blank, means for moving said movable head toward and from said stationary head, a plurality of separate forming elements positioned between said heads and adapted to receive said blank, guiding and supporting means for said forming elements, said forming elements being freely movable at random during the shaping operation to permit the blank to expand freely therebetween and thereinto and means for initially automatically spacing said forming elements.
- 35 19. In combination, in a machine for shaping metal, a stationary head and a movable head adapted to have a hollow blank clamped therebetween, means for admitting and maintaining fluid pressure within said blank, means for moving said movable head toward and from said stationary head, a plurality of separate forming elements positioned between said heads and adapted to receive said blank, guiding and supporting means for said forming elements, said forming elements being freely movable at random during the shaping operation to permit the blank to expand freely therebetween and thereinto, and means for moving said forming elements into initial and spaced position and relation during the retracting movement of the movable head.
- 40 20. In combination, in a machine for shaping metal, a stationary head and a movable head adapted to have a hollow blank clamped therebetween, means for admitting and maintaining fluid pressure within said blank, means for moving said movable head toward and from said stationary head, a plurality of separate forming elements positioned between said heads and adapted to receive said blank, guiding and supporting means for said forming elements, said forming elements being freely movable at random during the shaping operation to permit the blank to expand freely therebetween and thereinto, and means for moving said forming elements into initial and spaced position and relation during the retracting movement of the movable head, said means including elements associated with said guiding and supporting means selectively engaging said forming elements.
- 45 21. In combination in a machine for shaping metal, a stationary head and a movable head adapted to have a hollow blank clamped therebetween, means for moving said movable head toward and from said stationary head, a plurality of separate forming elements positioned between said heads and adapted to receive said blank, said forming elements being freely and independently movable during the forming operation, and means for retracting said forming elements by direct pull to a properly spaced initial starting position.

22. A method of corrugating thin-wall metal tubes, comprising positioning a tube relatively to a plurality of resiliently held spaced forming elements, subjecting the tube to internal and axial pressure while releasing said forming elements from their resiliently held condition to allow the forming elements to move freely and independently of each other. 80
23. A method of corrugating thin-wall metal tubes, comprising positioning a tube relatively to a plurality of spaced forming elements resiliently held in position at the beginning of the operation, subjecting the tube to internal and axial pressure while releasing the forming elements from their resiliently held condition to allow the forming elements to move freely and independently of each other to form a corrugated tube. 85
24. A method of corrugating thin-wall metal tubes, comprising positioning a tube relatively to a plurality of resiliently held spaced forming elements, subjecting the tube to internal and axial pressure while releasing said forming elements from their resiliently held condition to allow the forming elements to move freely and independently of each other to form a corrugated tube, removing the formed tube, and returning the forming elements to their initial spaced resiliently held position. 90
25. In combination in an apparatus for shaping metal from hollow blanks, a plurality of mold sections, means for resiliently holding said mold sections in spaced relation at the beginning of the operation, means for introducing an internal pressure into the blank, and means for collapsing said blank and simultaneously releasing said mold sections so as to allow them to move freely and at random during the collapsing movement. 100
26. A machine for shaping metal from a hollow blank, including in combination, a stationary head, a movable head, means for moving said movable head in both directions, a forming element including a plurality of mold sections positioned between said heads, said mold sections being so formed that when closed they provide a complete mold for the blank, means for movably supporting said mold sections so that they may move freely and independently with respect to each other and longitudinally of the blank and under the influence of the expanding metal of the blank, said supporting means being provided with elements adapted to selectively engage various mold sections during the retracting movement of the movable head. 105
27. A machine of the character described, including in combination, a stationary head, a movable head, a forming element for a hollow metal blank, including spaced supports, a plurality of shafts slidably mounted in said supports, a plurality of mold sections mounted upon said shafts between said heads, said mold sections being movable freely and independently with respect to each other during the forward movement of the movable head so that they may accommodate themselves longitudinally with respect to the blank under the influence of the expanding metal of the blank, each of said shafts being provided with an engaging element adapted to engage one of said mold sections and move said mold section back to its initial starting position. 110
28. A machine of the character described, including, in combination, a movable head, means for moving said head in either direction, a forming element including a plurality of mold sections adapted to receive a hollow blank, means for supporting said mold sections so that they may be moved longitudinally of the blank, said supporting means being provided with elements adapted to selectively engage various mold sections during the retracting movement of the movable head. 115
29. A machine of the character described, including, in combination, a forming element for a hollow metal blank including supports, a plurality of shafts slidably mounted in said supports, said forming element including a plurality of mold sections mounted upon said shafts, said mold sections being movable longitudinally of the blank, each of said shafts being provided with an engaging element adapted to engage one of said mold sections and move said mold section back to its initial starting position. 120
30. In combination in an apparatus for shaping metal from a hollow blank, an expansible and contractible mold formed of a plurality of mold sections supported for movement longitudinally of the blank when the blank is subjected to internal fluid and external longitudinal or axial pressure, and means for selectively retracting said mold sections and moving them into their initial starting position properly spaced with respect to each other. 125
31. In combination in an apparatus for shaping metal from a hollow blank, an expansible and contractible mold formed of a plurality of mold sections supported for movement longitudinally of the blank when the blank is subjected to internal fluid pressure and external longitudinal pressure, and means for selectively retracting said mold sections and moving them into their initial starting position properly spaced with respect to each other, said means being inoperative with respect to said mold sections during the shaping operation. 130
32. A machine for shaping metal from a hollow blank, including, in combination, a stationary head, a movable head or ram with means for moving said movable head or ram in both directions, a forming element including a plurality of mold sections between said stationary head and said movable head, said mold sections being so formed that when closed they provide a complete mold for the blank, means for movably supporting said mold sections so that they may move with respect to each other and longitudinally of the blank when the blank is subjected to the forming operation, said supporting means being provided with elements adapted to selectively engage various mold sections during the retracting movement of the movable head, and an operative connection between said movable head and said supporting means, whereby when the movable head is retracted the mold sections will be selectively moved to their initial starting position and properly spaced with respect to each other. 135
33. A machine of the character described, including, in combination, a stationary head, a movable head under pressure, a forming element for a hollow metallic blank, including spaced supports, a plurality of shafts slidably mounted on said supports, said forming element including a plurality of mold sections mounted upon said shafts between said stationary head and said movable head, said mold sections being movable longitudinally of the blank when the blank is subjected to a collapsing operation, each of said shafts being provided with a plurality of elements for resiliently holding a mold part in its proper starting position. 140
34. In combination in a machine for shaping metal, a stationary head and a movable head 145
- 150

adapted to receive a hollow blank therebetween, means for admitting and maintaining fluid pressure within said blank, means for moving said movable head toward and from said stationary head, a plurality of separate forming elements positioned between said heads and adapted to receive said blank, guiding and supporting means for said forming elements, and means for moving said forming elements into initial and spaced 10 position and relation during the retracting movement of the movable head.

35. In combination in an apparatus for shaping metal from a hollow blank, a plurality of mold sections, means for resiliently holding said mold 15 sections in spaced relation at the beginning of the operation, and means for releasing said resilient holding means after the collapsing operation has begun.

36. A method of corrugating thin wall metal 20 tubes, which comprises, positioning a tube relatively to a plurality of resiliently held spaced forming elements, introducing internal fluid pressure into the tube, subjecting the tube to axial pressure and simultaneously releasing the 25 forming elements to allow the forming elements to move freely and independently of each other to form the corrugated tube, removing the formed tube, and automatically returning the forming elements to their initial resiliently held position.

37. In a device of the character described, a plurality of mold sections adapted to receive a hollow blank, means for collapsing the blank to form a corrugated tube or blank while permitting the mold sections to have free and independent movement, and means for selectively retracting said mold sections and moving them to their original spaced position after removal of the corrugated tube or blank.

38. In a device of the character described for 40 shaping metal from a hollow blank, a plurality of mold sections, means for holding said mold sections in spaced relation, automatic means for releasing said holding means, and means for returning the mold sections to their spaced position 45 after the corrugating operation.

39. A method of corrugating hollow blanks, which comprises, positioning a tube relatively to a plurality of resiliently held spaced forming elements, subjecting the blank to internal pressure 50 and axial external pressure to collapse the blank and releasing the forming elements from their resiliently held condition to allow free and independent movement of the forming elements during the collapsing operation.

55

60

65

70

40. In combination, in an apparatus of the character described, a plurality of forming elements, means for resiliently holding said forming elements in spaced relation at the beginning of the operation, means whereby internal pressure and axial external pressure are applied to a hollow blank positioned relatively to said forming elements, and means for releasing said resilient holding means during the collapsing operation. 80

41. In a device of the character described for shaping metal from a hollow blank, the combination, including a plurality of forming elements, means for holding said forming elements in spaced relation, means whereby internal pressure and external axial pressure may be applied to a blank positioned with respect to said forming elements to collapse the blank, and automatic means for releasing said holding means during the collapsing operation. 85

42. In a device of the character described for shaping metal from a hollow blank, the combination, including a plurality of forming elements, means for resiliently holding said forming elements in spaced relation at the beginning 100 of the operation, means whereby internal pressure and external axial pressure may be applied to a blank positioned with respect to said forming elements to collapse the blank, and automatic means for releasing said holding means during 105 the collapsing operation.

43. In a device of the character described for shaping metal from a hollow blank, the combination, including a plurality of forming elements, means for holding said forming elements 110 in spaced relation, means whereby internal pressure and external axial pressure may be applied to a blank positioned with respect to said forming elements to collapse the blank, automatic means for releasing said holding means during 115 the collapsing operation, and means for returning said forming elements to their accurate initial spaced position after the corrugating operation has been completed.

44. In combination in an apparatus for shaping metal from a hollow blank, a plurality of mold sections, means for resiliently holding said mold sections in spaced relation at the beginning of the operation only, and means for releasing said resilient holding means at the beginning of 125 the collapsing operation.
